INDEXING MAT WINDING MACHINE

Joseph F. Stephens, Kansas City, Mo., assignor to Gustin-Bacon Manufacturing Company, Kansas City, Mo., a corporation of Missouri

Application January 18, 1955, Serial No. 482,566

12 Claims. (Cl. 242—55.1)

My invention relates to a mat winding machine and more particularly to an automatically indexing multiple unit machine for winding lengths of a mat or bats of fibrous material about mandrels.

In my copending application Serial No. 425,837, I have disclosed a single unit horizontal belt mat winding machine which has a high rate of production. In the machine disclosed in my said copending application, a horizontally positioned winding belt is driven and automatically manipulated successively to convey a mat to be wound, to wind the mat about a mandrel, and then to convey the wrapped mandrel to a discharge means. The rate of production on this automatic machine, while high, is limited by the times required to discharge a wrapped mandrel, to feed a new mandrel to the wrapping belt, and to manipulate the belt to winding position after each winding operation before the next winding operation begins. This limitation of the rate of production is not an especially critical factor where large diameter or thick windings are being made, since the winding time occupies a major portion of the machine cycle, and the capacity of the production line is restricted mainly by the winding time. It will be appreciated, however, that where smaller diameter or thinner walled tubes are being made, the potential capacity of the production line with respect to the number of units produced is substantially increased since the winding time is small relative to the mandrel feed and belt manipulation times. In order to achieve this potential capacity, a mat winding machine must be provided in which the readying of the winding belt and the discharge of the wound mandrels take place concomitantly with the winding operation.

I have invented an automatically indexing multiple unit mat winding machine capable of a greater rate of production than the machine of my said copending application. My novel indexing mat winding machine is provided with a plurality of winding belt units and a number of operating stations including a mandrel feeding station, a mat wrapping station, and a wound mandrel discharge station. At a time when operations are being performed, one winding unit may be disposed adjacent each of the respective operation stations so that several operations will proceed substantially concomitantly. While an empty mandrel is being fed to one winding unit at the feeding station, a mandrel is being wrapped on another unit at the wrapping station. At the same time, a wrapped mandrel is being discharged at the discharge station. When these operations have been completed, the means carrying the winding units is stepped or indexed to present an empty unit to the mandrel feed means, to position a new mandrel at the wrapping station, and to position a wrapped mandrel at the discharge station. My machine is provided with automatic means for controlling the manipulation of the respective winding units and for automatically stepping the mat winding unit support means when the various operations have been completed. My winding machine is particularly

2

adapted for the manufacture of windings having small diameters or windings which have thin walls, since it is capable of an extremely high rate of production.

One object of my invention is to provide an automatically indexing multiple unit mat winding machine which is capable of a high rate of production.

A further object of my invention is to provide a mat winding machine including a plurality of mat winding units and a number of operating stations, means for concomitantly performing operations with a number of mat winding units at the various stations, and means for automatically stepping the units to successive stations when such operations are completed.

Yet another object of my invention is to provide an automatically indexing multiple unit mat winding machine including a number of operating stations in which a mandrel delivery operation, a wrapping operation, and a discharge operation are performed by each of the units successively as the units are stepped from one station to the next.

A still further object of my invention is to provide an automatically indexing multiple unit mat winding machine which is particularly adapted to produce mat windings of small diameter or mat windings which have thin walls.

Other and further objects of my invention will appear from the following description.

In general, my invention contemplates the provision of a frame rotatably carrying a reel on which I arrange a number of circumferentially spaced mat winding units. Each of the mat winding units includes an endless wrapping belt and a plurality of belt carrying rollers. I provide means for continuously driving at least one of the rollers of each unit so that all the belts are continuously driven. Means are provided on each of the units for relatively moving a pair of belt supporting rollers to open the belt in order to discharge a wrapped mandrel and to present a portion of the belt to the mandrel feeding means. This roller operating means may also be actuated to wrap a portion of the belt about a mandrel to form a pocket of the belt in which the mandrel is disposed.

At one point on the reel supporting frame adjacent the periphery of the reel, I mount a mandrel feeding means including a drive for forcing an empty mandrel against the surface of the open belt and downwardly between the pair of relatively movable rollers against the action of a belt tensioning means. As the empty mandrel forces a portion of the belt downwardly between the movable rollers, the mandrel ends ride in guides provided in the reel. When the mandrel is seated in the bottom bearing portions of these guides, it is latched in position, and the relatively movable rollers are moved toward each other to form a pocket of the belt around the empty mandrel. This mat winding unit is now conditioned to receive a length of mat to be wrapped about the empty mandrel.

At another position adjacent the reel periphery, I arrange a mat feeding means to provide a winding station for my machine. While one mat feeding unit is being supplied with an empty mandrel, another unit which has received an empty mandrel during a previous operation is being supplied with a length of mat to be wrapped about the mandrel carried by the unit by means of that unit's wrapping belt.

At a third station adjacent the reel periphery, I arrange a discharge conveyor which receives a wrapped mandrel when the relatively movable belt supporting rollers are moved to a position to open the belt and the mandrel seating latches release the mandrel ends.

I provide automatic means for controlling the opera-

tions substantially simultaneously performed by the respective units at the feeding, wrapping, and discharge stations of my machine. This control means includes means for automatically stepping or indexing the mat winding unit support means when the operation at every station is complete, whereby the mat winding units are successively stepped to all operating stations.

In the accompanying drawings which form part of the instant specification and which are to be read in conjunction therewith, and in which like reference numerals indicate like parts in the various views:

Figure 1 is a diagrammatic sectional elevation of an indexing mat winding machine, containing one embodiment of my invention.

Figure 2 is a sectional view of my indexing mat winding machine taken generally along the line 2—2 of Figure 1.

Figure 3 is a fragmentary perspective view of my indexing mat winding machine.

Figure 4 is a fragmentary perspective view taken on an enlarged scale, with parts in section, showing the mandrel release means of my indexing mat winding machine.

Figure 5 is a schematic view of the automatic control circuit for my indexing mat winding machine.

More particularly referring now to the drawings, my indexing mat winding machine includes a frame having a base 10 and a pair of upstanding bearing support members 12 and 14. The frame side members 12 and 14 support a reel indicated generally by the reference character 16. Reel 16 includes sides 18 and 20 fixed by means of respective hubs 22 and 24 in spaced relationship on a hollow shaft 26 for rotation therewith. Channel irons 28, fixed by any suitable means such as welding or the like between sides 18 and 20, provide rigidity for the reel structure and maintain sides 18 and 20 in spaced relationship. Hollow shaft 26 is rotatably mounted in supports 12 and 14 by respective bearings 30 and 32.

Referring now to Figure 1, the reel 16 supports a number of circumferentially-spaced mat winding units, indicated generally, respectively, by reference numerals 34, 36, and 38. As can be seen by reference to Figures 1, 2, and 4, each of the mat winding units 34, 36, and 38 includes an endless belt 40 supported on a plurality of belt carrying rollers. Each unit includes a drive roller 42 fixed on a shaft 44 which is rotatably mounted in respective bearings 46 and 48 carried by sides 18 and 20. Each of the mat winding units also includes a pair of relatively movable belt supporting rollers 50 and 52. Roller 50 may conveniently be rotatably carried by shaft 54. Shaft 54 is slidably mounted in slots 56 provided in sides 18 and 20. Slots 56 are formed by guide members 58 secured to the sides 18 and 20 by any convenient means such as machine screws 60 or the like. In order to provide a means for moving shaft 54 and roller 50 back and forth in slots 56, I mount a pair of double-acting hydraulic cylinders 62 on brackets 66 carried by sides 18 and 20. The piston rod 68 associated with each of the cylinders 62 is coupled to an end of shaft 54 by a fitting 70. It will readily be appreciated that when rod 68 is actuated, shaft 54 moves along the slots 56. The other of the pair of movable rollers 52 may conveniently be rotatably carried by a shaft 72 slidably mounted in slots 74 formed in sides 18 and 20. In order to move shaft 72 back and forth in slots 74, I provide a pair of double-acting hydraulic cylinders 76 of any appropriate type known in the art. Cylinders 76 are mounted on brackets 78 carried by sides 18 and 20. The piston rod 80 associated with each of the cylinders 76 is coupled to an end of shaft 72 by a fitting 82. It will be appreciated that as rod 80 is actuated, shaft 72 is moved along the slots 74.

Each mat winding unit has an idler roller 84 carried by a shaft 86 rotatably mounted in bearings 88 in sides 18 and 20. I provide a mat tensioning roller 90 rotatably carried by a shaft 92, the ends of which ride in radial

slots 94 in sides 18 and 20. Rollers 90 are normally urged radially inwardly on the reel 16 by tension springs 96 fixed between points on the reel sides adjacent the respective hubs 22 and 24 and fittings 98 on the ends of shaft 92.

Referring now to Figures 1 and 2, in order to provide a means for driving the mat winding belts 40, as well as a means for driving the reel stepping means, I mount a motor 100 on a platform 102 secured to side 14 of the frame by any appropriate means such as bolts 104. Motor 100 is held on platform 102 by bolts 106. The drive shaft 108 of motor 100 carries a gear 110 thereon for rotation therewith. Gear 110 drives a gear 112 fixed on a shaft 114 which passes through the hollow shaft 26 carrying the reel 16. It is to be noted that while shaft 26 is rotatably mounted in bearings 30 and 32, shaft 114 is free to rotate within the hollow shaft 26. Any appropriate means, such as thrust collars 116 formed adjacent the ends of shaft 114, may be employed to position shaft 114 axially with respect to shaft 26 and to prevent shifting thereof. I mount a pair of sprocket wheels 118 and 120 on shaft 114 for rotation therewith adjacent the ends thereof. A pair of pitch chains 122 and 124 drivingly connect the respective sprocket wheels 118 and 120 with a pair of sprocket wheels 126 and 128 fixedly mounted on the ends of shaft 44 of mat winding unit 34. This shaft 44 of mat winding unit 34 carries a second pair of sprocket wheels 130 and 132 for rotation therewith adjacent the respective sprocket wheels 126 and 128. The respective sprocket wheels 130 and 132 are arranged to drive pitch chains 134 and 136. Chain 134 passes around and drives respective sprocket wheels 130 fixed on the shafts 44 of the respective mat winding units 36 and 38. Similarly, chain 136 drives respective sprocket wheels 132 fixed on the shafts 44 of the respective mat winding units 36 and 38. It will readily be appreciated that the wrapping belt drive just described drives all the mat winding belts 40 continuously whenever motor 100 is energized.

In order to provide a means for stepping the reel 16 when the operations at each station have been completed, I mount the driving member 138 of a one-revolution clutch, indicated generally by the reference character 140, on shaft 108 for rotation therewith. Clutch 140 may be of any type known to the art, such, for example, as that shown and described in U. S. Patent No. 2,140,737. Clutch 140 includes a driven member 142 fixed on a shaft 144 rotatably mounted in a bearing 146 carried by member 14. A clutch operating member 148 is adapted to be actuated to release the drive member 142 of clutch 140 to permit shaft 144 to be driven through one revolution. A spur gear 150 fixed on shaft 144 for rotation therewith drivingly engages a gear 152 fixed on shaft 26 for rotation therewith. It will readily be understood that when the actuating member 148 of clutch 140 is operated to release the driven member 142, shaft 144 will be driven through a single revolution. I select a ratio between gear 150 carried by shaft 144 and gear 152 carried by shaft 26 such that when shaft 144 makes a single revolution, shaft 26 makes a third of a revolution.

I provide a mandrel feed station, a mat winding station, and a discharge station at equally spaced positions around and adjacent to the periphery of reel 16. Conveniently, I mount three circumferentially equally-spaced mat winding units on the reel 16. The arrangement is such that, at any time when operations are being performed, one of the mat winding units is adjacent each station. Since shaft 26 carrying reel 16 makes a third of a revolution when one-revolution clutch 140 is actuated, the mat winding units carried by the reel are stepped successively from station to station after each group of operations is completed.

Referring now to Figure 3, I provide an empty mandrel feed station adjacent the top of the reel. A mandrel support rack including a pair of spaced inclined rails 154 may

be supported by any suitable means from the machine frame. Empty mandrels 156 are supported by their respective shafts 158 on rails 154. Since rails 154 are inclined downwardly toward the reel 16, the mandrel shafts 158 are fed by gravity to a pair of substantially vertically directed guideways 160. Each of the guideways 160 is formed by a substantially vertically depending portion 162 of a rail 154 and by a mandrel shaft retaining member 164. The guideways 160 direct a mandrel shaft 158 to a position where its ends are retained by a pair of mandrel feed releases latches, each of which is indicated generally by the reference character 166.

As can be seen by reference to Figure 4, each of the mandrel feed release latch assemblies 166 includes a housing 168 in which I slidably mount a first finger 170 in an axial bore 172 formed in the housing. Finger 170 is normally urged to the left, as viewed in Figure 4, by a coil spring 174 bearing between the base of housing 168 and an annular flange 176 formed adjacent an end of finger 170. Conveniently, finger 170 may be the armature of a solenoid, the winding 178 of which is carried by a recess 180 in housing 168 so as to surround finger 170. When winding 178 is energized, finger 170 is moved to the right, as viewed in Figure 4, against the action of spring 174 to withdraw the finger from under the mandrel shaft 158 to permit the mandrel to move downwardly against the surface of an open belt 40. I slidably mount a retaining finger 182 within a second bore 184 formed in housing 168. Finger 182 is operatively connected with finger 170 by a lever 186 disposed in transverse recess 188 and pivotally carried by a pin 190. One end of lever 186 engages in a recess 192 formed in finger 182 and the other end of lever 186 engages in a recess 194 in finger 170. As finger 170 moves to the right when solenoid 178 is energized, it drives lever 186 to move retaining finger 182 to the left, as viewed in Figure 4. While finger 170 is so moved to release a mandrel, finger 182 is moved to a position to support the next succeeding mandrel and prevent its interference with the mandrel being fed to a mat winding unit. When winding 178 is de-energized, spring 174 returns the fingers to their normal positions, shown in Figure 4, and the mandrel which was caught by fingers 182 drops to be retained by fingers 170.

Each of the sides 18 and 20 is formed with a radial slot 192 adjacent each of the mat winding units to receive an end of a mandrel shaft which is being fed to the corresponding mat winding unit. In order to provide a means for driving a mandrel into the open belt between rollers 50 and 52 against the action of tension roller 90, I mount a mandrel feed rack, indicated generally by the reference character 194, in guides 196 carried by the machine frame. Rack 194 includes a pair of sides 198 and a cross bar 200 which connects sides 198. Each of the sides 198 is formed with teeth 202 for engagement with drive gears 204 carried by the mandrel feed drive shaft 206 for rotation therewith. It will be appreciated that as shaft 206 rotates in a clockwise direction, as viewed in Figure 3, rack 194 is driven downwardly. When the direction of rotation of shaft 206 is reversed, the rack is returned to the position shown in Figure 3. A pair of arms 208 pivoted on pins 210 carried by the respective sides 198 of rack 194 provide a driving engagement between the rack and the mandrel shaft 158 of the mandrel being fed to a mat winding unit. Springs 212 connected between sides 198 and arms 208 normally urge arms 208 in a counterclockwise direction, as viewed in Figure 3. A pair of stops 214 carried by sides 198 limit the movement of arms 208 under the action of springs 212. After the mandrel release means 166 has operated to release a mandrel for movement toward belt 40, rack 194 is driven to engage arms 208 with the ends of the mandrel shaft. As the rack continues to move downwardly, the empty mandrel 156 is forced into the belt 40 between rollers 50

and 52 against the action of tension roller 90. As this action takes place, tension roller 90 is drawn up in slots 94 against the action of springs 96. When a mandrel 156 has been driven into belt 40 so that the mandrel shaft ends are positioned in journals formed at the bottom of radial slots 192, the mandrel feed drive motor (not shown) connected to shaft 206 in any appropriate manner is reversed in a manner to be described hereinafter to return the feed rack to the position shown in Figure 3.

In order to retain the mandrel shaft ends in the journals in the bottoms of slots 192, I mount a pair of solenoid-operated latches 216 adjacent the bottoms of slots 192. Each of the latches 216 is pivoted on a pin 218 in one of the sides 18 or 20 and is operatively connected with the armature 220 of one of a pair of solenoids 222 carried by the respective sides 18 and 20. When a mandrel shaft has been positioned in the bottoms of slots 192, solenoids 222 are energized in a manner to be described hereinafter to operate latches 216 to hold the mandrel firmly in place. After the mandrel has been so positioned and latched, the hydraulic cylinders 62 and 76, associated with the respective movable rollers 50 and 52, are operated to wrap the belt about the mandrel to form a pocket. The relative disposition of the parts of the mat winding unit at this time is as shown for unit 36 in Figure 1.

While a mat winding unit, such as the unit 34, is receiving an empty mandrel in the manner just described, another of the units, such as the unit 36, is in a position to receive a length of mat. As can be seen by reference to Figure 1, a mat feed conveyor, indicated generally by the reference character 224, is disposed adjacent the unit 36. While unit 34 is being fed an empty mandrel, unit 36 is being fed a length of a mat or bat of fibrous material 226 carried by conveyor 224. As the mat 226 is being fed to the unit 36, it interrupts a light beam from a light source 228 to a photoelectric relay unit 230. The photoelectric unit 230 forms a part of the automatic control circuit to be described hereinafter.

While unit 34 is receiving an empty mandrel and while unit 36 is being fed with mat, the third unit 38 is discharging a wrapped mandrel. When unit 38 reaches the discharge station, the automatic control means to be described hereinafter de-energizes the latch solenoids 222 associated with this station to release the mandrel shaft ends. At the same time, the movable roller cylinders 62 and 76 of this unit are reversed to open the belt and deliver the wrapped mandrel to a chute 232 which delivers the wrapped mandrel to a discharge conveyor (not shown).

When the operations at each of the mandrel feeding, mat winding and wrapped mandrel discharge stations have been completed, the actuating member 148 of one-revolution clutch 140 is operated to permit reel 16 to be stepped through a third of a revolution. When this operation takes place, unit 34, which has just received an empty mandrel, advances to the wrapping station, which formerly was occupied by unit 36; unit 36, the mandrel of which has just been wrapped with mat, advances to the discharge station, which formerly was occupied by unit 38; and unit 38, which has just delivered a wrapped mandrel, is again advanced to the mandrel feed station, which formerly was occupied by unit 34. While I have shown my mat winding machine as including only three units, it will readily be understood that I may, for example, employ six units and step reel 16 through only one-sixth of a revolution after each operation.

Referring now to Figure 5, the electrical control circuit for my mat winding machine includes a pair of supply lines 234 and 236 connected respectively to a suitable source of electrical power having terminals 238 and 240. The field winding of the main drive motor 100 is indicated schematically in the figure by reference character 242. One side of winding 242 is connected to line 234 by a pair of normally open contacts 244. The other side of winding 242 is connected to line 236. The armature 246

of motor 100 is connected at one side to line 234 by normally open contacts 248 and at the other side to line 236.

In order to drive shaft 206 to feed mandrels to a mat winding unit, I provide a mandrel feed drive motor including a field winding 250, one side of which is connected by normally open contacts 252 to line 234 and the other side of which is connected to line 236. The brake solenoid 251 associated with the mandrel feed drive motor may conveniently be connected at one side to line 234 by a pair of normally closed contacts 253 and at the other side to line 236. The armature 254 of the mandrel feed drive motor is connected to line 234 by normally open contacts 256 at one side and at the other side is connected to line 236 by normally open contacts 258 and normally closed contacts 260 in series. It will readily be appreciated that when both contacts 256 and 258 are closed, the mandrel feed drive motor is energized to rotate shaft 206 in one direction. Conveniently, when these contacts are closed, shaft 206 is rotated to drive rack 194 in a direction to feed mandrels to belt 40.

In order to provide a means for reversing the direction of rotation of shaft 206, I provide reversing connections for the mandrel feed drive motor. These connections include a pair of normally open contacts 262 for connecting the side of armature 254 to which contacts 258 are connected to line 234. To complete the reversing connections, a pair of normally open contacts 264 connect the side of armature 254 to which contacts 256 are connected to line 236. As will be explained hereinafter, when contacts 262 and 264 close to reverse the direction of rotation of the mandrel feed drive motor, normally closed contacts 260 are opened to interrupt the forward drive circuit of the motor.

In order to start the motor 100 and the mandrel feed drive motor to begin operations, I provide a start button 266 having two pairs of respective contacts 268 and 270 associated therewith. Contacts 268 are connected in series with a mandrel drive motor starting relay winding 272 and a stop switch 287 between lines 234 and 236. Similarly, contacts 270 are connected in series with a main drive motor starting relay winding 274 and switch 287 between lines 234 and 236. When start button 266 is pressed, contacts 268 and 270 are closed to complete the circuits of their respective windings 272 and 274. When winding 272 is energized, it opens contacts 253 and closes contacts 252, 258 and 256 through a linkage 276 to de-energize brake solenoid winding 251 and to energize the mandrel feed drive motor to drive rack 194 downwardly in a feeding direction. In order to maintain the circuit of winding 272 after the button 266 has been released, I provide a holding circuit including a pair of normally open contacts 278 adapted to be closed by linkage 276. One of the contacts 278 is connected to one side of winding 272 by a conductor 280. The other of the contacts 278 is connected by normally closed contacts 282 to line 236. When winding 272 is energized by the closing of push button contacts 268, contacts 278 close to maintain the circuit of winding 272. This holding circuit may be traced from line 234, through switch 287, through winding 272, through conductor 280, through contacts 278, and through normally closed contacts 282 to line 236.

When contacts 270 are closed upon operation of button 266, winding 274 is energized to close contacts 244 and 248 through a linkage 282, thus starting the main drive motor 100. In order to maintain the circuit of winding 274 after button 266 has been released, I provide a holding circuit including a pair of normally open contacts 284 which are operated by linkage 282. One of the contacts 284 is connected to the side of winding 274 connected to contacts 270 by a conductor 286. The other of the contacts 284 is connected to line 236. After push button 266, which closes contacts

274 and thereby closes contacts 284, is released, the circuit to winding 274 may be traced from line 234, through switch 287, through winding 274, through conductor 286, through the now closed contacts 284 to line 236.

In order to energize the mandrel release latch solenoid windings 178 at the feeding station, I connect windings 178 in parallel between lines 234 and 236. One side of each of the windings 178 is connected by normally open contacts 288 to line 234, and the other side is connected by normally closed contacts 290 to line 236. As can be seen by reference to Figure 5, contacts 288 are closed when linkage 276 is operated to energize windings 178 and actuate the mandrel release latch fingers 170. After the mandrel release latch fingers 170 have been actuated to release a mandrel, and the mandrel rack 194 has been driven until the mandrel shaft ends are positioned in the bottoms of slots 192, rack 194 engages and actuates a mandrel seating limit switch 292. This mandrel seating limit switch 292 is connected in series with a mandrel seating relay winding 294 between lines 234 and 236. At this time the mandrel seating latches 216 of the mat winding unit positioned adjacent the feeding station are to be operated. It will readily be appreciated that the mandrel seating latches 216 must be closed at the feeding station, kept closed at the winding station, and released at the discharge station. Accordingly, the control means for these latches is conditioned to operate the latches in two positions of the reel and is de-energized to release the latches in the third position of the reel. At any particular position of the reel, the control means for the seating of latches of the unit adjacent the mandrel feed station is conditioned to operate. At the same time, the latches of the unit positioned adjacent the winding station are maintained closed and the latches of the unit positioned adjacent the discharge station are opened. Referring again to Figure 5, the windings 296 of the pair of mandrel seating latch solenoids 222 of the mat winding unit adjacent the feeding station are each connected at one side to line 234. The other sides of each of the windings 296 are connected by a pair of normally open contacts 298 to a contact 300 of a rotary switch including a brush 302 which is connected to line 236. The sides of windings 296 connected to contacts 298 are also connected by normally open contacts 304 to a contact 306 of a second rotary switch including a contacting segment 308 which is connected to line 236. Contacts 298 are arranged to be closed by a linkage 310 which is operated by the energization of the mandrel seating relay winding 294. If this relay winding 294 is energized to close contacts 298 and the brush 302 engages contact 300, the circuit to the parallel-connected windings 296 is complete from line 234, through windings 296, through the now-closed contacts 298, through contact 300 and brush 302 to line 236. Brush 302 may conveniently be carried by shaft 26 so that it engages stationary contact 300 at only one position of reel 16. In order to maintain the circuit of windings 296 while the corresponding unit is at the winding station after the reel has been stepped, I connect a holding winding 312 in parallel with windings 296. Winding 312 is adapted when energized to close contacts 304 through a linkage 314. Since winding 312 is connected in parallel with windings 296, it also will be energized when contacts 298 are closed and when brush 302 engages contact 300. When brush 302 leaves contact 300 as the reel is stepped, the circuit to windings 296 and 312 is maintained from line 234 through windings 296 and 312, through the now-closed contacts 304, through contact 306, and through segment 308 to line 236. Segment 308 may also conveniently be carried by shaft 26. Its dimensions are such that it maintains the holding circuit provided by contacts 304 for the period of time when the corresponding unit is at the winding station after it leaves contact 300.

The mandrel seating latch windings 316 associated with

another of the mat winding units, which may, for example, be the unit 36 adjacent the winding station, are connected at one side by a common conductor to line 234. The other sides of these windings 316 are connected by a pair of normally open contacts 318 to a contact 320 associated with brush 302. Contacts 318 are arranged to be closed by the linkage 310 when the mandrel seating relay winding 294 is energized. When winding 294 is energized to close contacts 318 and brush 302, engages contact 320, the circuit to windings 316 is complete from line 234, through windings 316, through now-closed contacts 318, through contact 320 and brush 302 to line 236. In order to maintain the circuit of windings 316 for the necessary period of time after brush 302 leaves contact 320, I connect a holding winding 322 in parallel with windings 316. Winding 322 is adapted when energized to close a pair of normally open contacts 324 by means of a linkage 326. Contacts 324 are disposed between winding 322 and a contact 327 associated with segment 308. After brush 302 leaves contact 320, the circuit of windings 316 is maintained from line 234 through parallel-connected windings 316 and 322, through now-closed contacts 324, through a contact 327, and through segment 308 to line 236.

In order to operate the mandrel seating latch solenoids 328 associated with the third mat winding unit which may, for example, be the unit 38 disposed adjacent the discharge station, I connect the associated latch solenoid windings 328 at one side to line 234 and at the other side through normally open contacts 330 to a third contact 332 associated with brush 302. Contacts 330 are arranged to be closed by linkage 310 upon the energization of the mandrel seating relay winding 294. When winding 294 is energized to close contacts 330 and brush 302, engages contact 332, the circuit to windings 328 is complete from line 234, through windings 328, through now-closed contacts 330, through contact 332 and brush 302 to line 236. In order to maintain the circuit of windings 328 for the necessary period of time after brush 302 leaves contact 332, I connect a holding relay winding 334 in parallel with windings 328. Winding 334 is adapted when energized to close a pair of normally open contacts 336 by means of a linkage 338. Contacts 336 are connected between windings 334 and a third contact 340 associated with segment 308. After brush 302 leaves contact 332, the circuit to windings 328 is maintained from line 234, through windings 328 and 334, through contacts 336, through contact 340 and segment 308 to line 236. It will readily be appreciated that since winding 334 is connected in parallel with windings 328, it will be energized when brush 302 engages contact 332 and when contacts 330 are closed.

It is to be noted that the arrangement of segment 308 and its corresponding contacts, and brush 302 and its corresponding contacts, is such that the latches of the various mat winding units are actuated in the proper sequence. Both segment 308 and brush 302 may conveniently be carried by shaft 26 to reel 16 and arranged to engage stationary, equally circumferentially-spaced contacts. The direction of rotation of segment 308 and brush 302 is clockwise, as is indicated in Figure 5. When segment 308 first engages a contact corresponding to a particular mat winding unit, brush 302 also engages a contact corresponding to this unit. Consequently, when the associated mandrel seating relay contacts close, the latch solenoids 55 of this unit are energized. When the reel is next stepped, the segment 308 maintains its engagement with the contact associated with the particular unit, so that the mandrel latch solenoids remain engaged. When the reel is again stepped, segment 308 leaves the contact, and the mandrel latch solenoids are de-energized to release the mandrel. This sequence of operation is the same for each of the mat winding units 34, 36, and 38. When a unit is at the mandrel feed station, the latch solenoid circuits are conditioned to close the latches when the mandrel seat-

ing limit switch is engaged. When the reel is stepped to move the unit to the mat winding station, the latch solenoid winding circuits are maintained through segment 308. When the reel is again stepped to move the unit to the discharge station, segment 308 leaves the associated contact to interrupt the mandrel solenoid holding circuits and permit the latches to release the mandrel.

After an empty mandrel has been fed to one of the mat winding units so as to be seated in the bottom of the radial slots 192, the mandrel feed drive motor must be reversed to return drive rack 194 to its initial position. The reversal of the mandrel feeding drive motor may readily be accomplished by closing normally open contacts 262 and 264 and at the same time opening contacts 260. In order to open contacts 260 and close contacts 262 and 264, I provide a reversing relay winding 342 adapted when energized to operate contacts 260, 262, and 264 through a linkage 344. I connect one side of winding 342 to line 234 and the other side to line 236 by means of a pair of normally open contacts 346. Contacts 346 are closed by linkage 310 when the mandrel seating relay winding 294 is energized by the closing of the mandrel seating limit switch 292. When contacts 346 close, winding 342 is energized to operate contacts 260, 262, and 264 to reverse the mandrel feed drive motor. In order to maintain the circuit of relay winding 342 after rack 194 is disengaged from the mandrel seating limit switch 292, I connect a holding relay winding 348 in parallel with winding 342 so as to be energized when contacts 346 close. Winding 348 is connected by normally open contacts 350 and normally closed contacts 352 to line 236. When energized, winding 348 closes contacts 350, through a linkage 354 to maintain the reversing winding circuit after the rack 194 releases the mandrel seating limit switch 292.

After an empty mandrel has been seated in slots 192 and latched in place by latches 216, the movable rollers 50 and 52 of the unit to which the mandrel has been fed are moved toward one another to form a pocket of the belt 40 about the mandrel. To accomplish this end, fluid under pressure must be fed to the proper side of each of the cylinders 62 and 76 associated with the unit, and the other sides of these double-acting cylinders should be connected to the exhaust. As can be seen by reference to Figure 3, each cylinder 62 is provided with a fluid connection 356 at one end thereof and a second fluid connection 358 at the other end thereof. Similarly, each of the cylinders 76 is provided with connections 360 and 362. When the movable rollers 50 and 52 are to be moved toward one another to form a pocket of belt 40 about a mandrel, lines 356 and 362 should be connected to a source of fluid under pressure, and lines 358 and 362 should be connected to the exhaust. Referring again to Figure 5, in order to make these connections, I provide solenoid control valves each associated with one of the respective mat winding units. For example, associated with the unit positioned adjacent the feeding station, I arrange a valve 364. In one position of the valve a source of pressure P is connected to lines 356 and 362 of the associated unit to actuate movable rollers 50 and 52 to the closed position. In this position of the valve, lines 358 and 360 are connected to an exhaust E. For convenience, lines 356 and 362 of each unit, which correspond to the closed position of the movable rollers when pressure is applied thereto, have been designated by the outlet C of the valves shown in Figure 5. Similarly, lines 358 and 360, which correspond to the open belt position when pressure is applied thereto, have been indicated as the outlet O of each of the valves shown in Figure 5. The valve 364 corresponds to the mat winding unit which is adjacent the mandrel feeding station. It is desirable that this valve be actuated to connect a source of pressure to close the movable rollers after a mandrel has been seated in slots 192. In order to actuate valve 364 to

accomplish this result, I provide a solenoid winding 366 arranged to actuate valve 364 through a suitable linkage. In order to energize winding 366 to operate valve 364 to close rollers 50 and 52, I connect one side of winding 366 through a pair of normally open contacts 370 to line 236. I connect the other side of winding 366 to line 234 by normally open contacts 372. In order to close contacts 370 and 372 to energize solenoid 366, I connect a relay winding 374 at one side through a pair of normally open contacts 376 to line 236. I connect the other side of winding 374 to a conducting segment 378 with which a brush 380 connected to line 234 is associated. Contacts 376 are closed by linkage 310 when the mandrel seating limit switch closes to energize winding 374 to close contacts 370 and 372 to energize solenoid 366 to actuate valve 364 to connect lines 356 and 362 of the associated mat winding unit hydraulic cylinders to a source of fluid under pressure to close the movable rollers 50 and 52. At the same time, lines 358 and 360 are connected to the exhaust. This is the condition of valve 364 indicated in Figure 5. In order to maintain the circuit of solenoid 366 after the mandrel seating limit switch 292 has been released by rack 194, I connect a holding winding 382 in parallel with winding 374 so as to be energized when winding 374 is energized. Winding 382 is adapted to close a pair of normally open contacts 384 through a linkage 386. Contacts 384 are connected between winding 382 and line 236. It will be appreciated that after the movable rollers 50 and 52 of a unit have been closed to form a pocket of belt 40 about a mandrel, they are to be maintained in the closed position during the period of time when the unit is at the winding station and until the reel has been stepped to advance the unit to the discharge station. In order to reverse the direction of actuation of valve 364 so as to open the movable rollers of the unit with which the valve is associated, I provide a second solenoid 368 for actuating valve 364 in a direction opposite to the direction in which the valve is actuated by solenoid 366. I connect one side of solenoid 368 to line 234 by a pair of normally open contacts 390 and the other side of winding 368 to line 236 by a pair of normally open contacts 388. When contacts 388 and 390 are closed, valve 364 is actuated to connect the lines 358 and 360 of the hydraulic cylinders of the associated mat winding unit to a source of fluid under pressure and to connect lines 356 and 362 of hydraulic cylinders of the associated mat winding unit to the exhaust. In order to provide a means for closing contacts 388 and 390 when the unit arrives at the discharge station, I provide a relay winding 392 connected at one side to line 236 and at the other side to a second segment 394 associated with brush 380. Conveniently, I arrange brush 380 on the shaft 26. The arrangement is such that brush 380 engages segment 378 when the associated unit is at the feeding station, so that the movable rollers 50 and 52 will be closed when the mandrel seating limit switch 292 is engaged. This engagement of brush 380 is maintained during the stepping of reel 16 to keep the movable rollers in a closed position until the corresponding unit arrives at the discharge station. When the unit arrives at the discharge station, brush 380 engages segment 394 to complete the circuit of reversing relay winding 392 from line 234, through brush 380, through segment 394, and through winding 392 to line 236. When winding 392 is energized, contacts 388 and 390 are closed through a suitable linkage to energize solenoid 368. It will be readily understood that segments 378 and 394 are separated by insulation so that the holding circuit provided by winding 382 is interrupted as brush 380 travels from segment 378 to segment 394, thus de-energizing the solenoid 366 which closes the movable rollers. When solenoid 368 is energized, lines 356 and 362 are connected to the exhaust, and lines 358 and 360 are connected to the source of fluid under pressure. I provide similar valve arrangements for the remainder

of the mat winding units. For the mat winding unit positioned adjacent the winding station, I arrange valve 396 similar to valve 364. Valve 396 is actuated by a suitable linkage driven by a solenoid 400. Solenoid 400 is connected at one side to line 234 by a pair of normally open contacts 404 and at the other side to line 236 by a pair of normally open contacts 402. When contacts 402 and 404 are closed, solenoid 400 actuates valve 396 to move the corresponding movable rollers to a closed position. I provide a relay winding 406 connected at one side to line 236 by normally open contacts 408 and at the other side to a segment 410 with which a brush 412, connected to line 234, is associated. Contacts 408 are closed by linkage 310 operated by the mandrel seating relay winding 294 to energize winding 406 when brush 412 contacts segment 410. When winding 406 is so energized, contacts 402 and 404 close to energize solenoid 400 to drive valve 396 to actuate the corresponding hydraulic cylinders to close the movable rollers of the unit. A holding coil 414 connected in parallel with winding 406 is arranged to close normally open contacts 416 connected between line 236 and coil 414 by a linkage 418. The circuit to coil 406 is thereby maintained. In order to reverse the direction of actuation of valve 396 so as to open the corresponding movable rollers when the unit arrives at the discharge station, I provide a second solenoid 398 connected at one side to line 236 by a pair of normally open contacts 420 and at the other side to line 234 by a pair of normally open contacts 422. When contacts 420 and 422 are closed, solenoid 398 is energized to operate valve 396 in a direction to cause the corresponding movable rollers to be opened. In order to operate contacts 420 and 422, I provide a relay winding 424 connected between line 236 and a segment 426 associated with brush 412. As the reel is stepped, brush 412 moves from segment 410 to segment 426 to interrupt the holding circuit of relay winding 406 and complete the circuit of winding 424. Winding 424 when energized closes contacts 420 and 422 to energize solenoid 398 actuating valve 396 in a direction to open the corresponding movable rollers. It is to be understood that the relative length of segments 410 and 426 is such that the movable rollers close when the unit is at the feeding station and the mandrel seating limit switch 292 is actuated, and the rollers do not open until the unit arrives at the discharge station. For the unit which corresponds to the unit at the discharge station, I provide a valve 428 which is actuated by a suitable linkage driven by a solenoid 432. In order to energize solenoid 432 to drive valve 428 to move the corresponding movable rollers to the closed position, I connect one side of winding 432 to line 234 by normally open contacts 436. I connect the other side of winding 432 to line 236 by normally open contacts 434. In order to actuate contacts 434 and 436, I provide a relay winding 438 connected at one side by normally open contacts 440 to line 236 and connected at the other side to a segment 442, with which a brush 444 connected to line 234 is associated. Contacts 440 are closed by linkage 310 to energize winding 438 to close contacts 434 and 436 to energize solenoid 432 to actuate valve 428 to move the corresponding movable rollers to closed position. In order to maintain this circuit of winding 438 after the mandrel seating limit switch 292 is released, I connect a winding 446 in parallel with winding 438 so as to be energized when winding 438 is energized. Winding 446 operates a linkage 448 to close normally open contacts 450 connected between winding 446 and line 236 to maintain the circuit of winding 438. In order to actuate valve 428 in a direction to open the corresponding movable rollers, I provide a second solenoid 430 connected at one side to line 234 by a pair of normally open contacts 454 and connected at the other side to line 236 by a pair of normally open contacts 452. When contacts 452 and 454 are closed, winding 430 is

energized to actuate valve 428 in a direction opposite to the direction in which the valve is actuated by the energization of winding 432. When the winding 430 is so energized, the corresponding movable rollers are opened. To operate contacts 452 and 454 to energize solenoid 430, I provide a relay winding 456 connected between line 236 and a segment 458 associated with brush 444. As the reel is stepped, brush 444 engages segment 458 when the corresponding unit is at the discharge station to energize winding 456 and close the contacts 452 and 454 to energize solenoid 430 and to open the corresponding movable rollers.

It will readily be appreciated that all the brushes 380, 412, and 444 are carried by shaft 26 for rotation therewith. The relative circumferential spacing of the brushes is such that the brush corresponding to the unit at the mandrel feed station engages a segment such as segment 378 so that the rollers may be moved to a closed position when the mandrel seating limit switch is actuated. The brush corresponding to the unit at the winding station engages a segment such as the segment 410, so that its associated solenoid is maintained energized in a direction to close the corresponding movable rollers. The brush 444 is so positioned that it engages a segment, such as the segment 458, to energize the solenoid which operates valve 428 to move the corresponding movable rollers to open position.

After a mandrel has been fed to the open belt and latched in the bottoms of slots 192 by latches 216, and the movable rollers 50 and 52 have been closed, the rack 194 on its return engages and actuates a return limit switch 460 connected at one side to line 234 and at the other side to line 236 by a return relay winding 462. When winding 462 is energized, it operates a linkage 465 to open normally closed contacts 352, and thereby interrupt the mandrel feed drive motor reversing circuit. It also opens normally closed contacts 290 to de-energize the mandrel feed latch solenoids 178 and permit them to reset. This winding 462 also opens normally closed contacts 282 to interrupt the holding circuit for the main control relay winding 272 and permit contacts 252, 253, 256, and 288 to open and contacts 253 to close.

In order to step the reel when a group of operations have been completed, I connect a solenoid 464 at one side to line 236 by a pair of normally open contacts 466. The other side of solenoid 464 is connected by normally open contacts 468 to line 234. Contacts 466 are closed upon the energization of winding 462 when rack 194 engages the rack return limit switch 460. The normally open contacts 468 are momentarily closed by the operation of a timer which will be described in detail hereinafter. When both contacts 468 and contacts 466 are closed, solenoid 464 is momentarily energized to operate the actuating member 148 of one-revolution clutch 140 to release the driven member 142 to permit a single revolution of shaft 144. This single revolution of shaft 144 steps the reel through a third of a revolution by means of gears 150 and 152. The stepping of the reel 16 is automatically accomplished at the end of a group of operations by means of a photo relay actuated from phototube 230. The photo relay 470 is connected at one side to line 234 and at the other side to line 236 through a winding 472. Winding 472 is adapted when energized to close a pair of normally open contacts 474 through a linkage 476 when the light beam from source 228 to phototube 230 is interrupted by a length of mat from the conveyor 224. Contacts 474 are connected in series with a timer relay winding 478 between lines 234 and 236. Winding 478 when energized initiates the action of a timing device 482 through a linkage 480. A predetermined time after the energization of winding 478, timer 482 operates to energize momentarily a winding 484 connected in series with timer 482 between lines 234 and 236. The energization of winding 484 closes contacts 468 to step the reel. It is to be noted also that energization of winding 472 closes

a pair of contacts 486 connected between the conductor 280 and line 236. This closure completes the circuit to the main control relay 272 to begin a new group of operations.

- 5 The time delay between the operation of photo relay 470 and the operation of timer 482 is so selected that all operations will be complete by the time the timing device 482 operates. That is, the feeding of an empty mandrel to the mat winding unit positioned adjacent thereto will 10 have been completed so that the contacts 466 associated with the mandrel feed rack return relay winding 462 will be closed. Consequently, when contacts 468 are closed upon the operation of the timer 482, the solenoid 464 will be energized to actuate the one-revolution clutch 140 to step the reel.

It will be appreciated that when operations are initiated, the mat winding unit at the winding station will carry no empty mandrel, and no winding operation will be performed. Consequently, timer 482 will not operate 20 after a mandrel has been fed to the mat winding unit opposite the mandrel feed station. In order to energize solenoid 464 to step the reel after this initial delivery of an empty mandrel to the unit positioned adjacent the mandrel feed station, I connect a manually operable push-button switch 488 in parallel with contacts 468. After an empty mandrel has been fed to a mat winding unit, when operation of the machine is being set up, switch 488 may be actuated to energize solenoid 464 and step the reel. It will be appreciated that at this time, contacts 466 have been closed by winding 462 so that the circuit to solenoid 464 may readily be completed.

In operation, assuming the relative disposition of the mat winding units to be as shown in Figure 1, so that the machine is operating, all the belts 40 will be continuously driven, since the belt drive motor was started by the operation of push-button switch 266 to close contacts 244 and 248. Holding contacts 284 serve to maintain the circuit of winding 274 to keep contacts 244 and 248 closed until stop button 287 is operated to stop the 40 machine.

As a length of mat 266 is fed to the unit 36, it interrupts the beam of light from light source 228 to phototube 230. When this occurs, photo relay 470 operates in a manner known to the art to energize winding 472 and close contacts 474 and 486. When contacts 486 close, they complete the circuit of winding 272 from line 234, through switch 287, through winding 272, through line 280, through contacts 486 to line 236. The energization of winding 272 opens contacts 253 in the mandrel feed drive motor brake solenoid circuit to de-energize solenoid 251 to release the brake. The energization of winding 272 also closes mandrel feed drive motor field winding contacts 252 and closes the down drive contacts 258 and 256 of the mandrel feed drive motor armature. 55 At the same time, contacts 288 are closed to energize the mandrel feed release solenoids 178. When solenoids 178 are energized, fingers 170 move to the right as viewed in Figure 4, to release the ends of an empty mandrel shaft 158 to permit the mandrel to be fed downward, 60 toward an open belt 40. At the same time fingers 182 move to the left, as viewed in Figure 4, to catch and retain the shaft ends of the next empty mandrel. As the mandrel drive motor rotates, it drives shaft 206 in a direction to drive rack 194 downwardly as viewed in Figure 65 3. As rack 194 moves downwardly, arms 208 engage the ends of the released mandrel shaft 158 to force the mandrel 156 downward into belt 40 between movable rollers 50 and 52 against the action of tensioning roller 90. When rack 194 reaches the limit of its downward movement, the ends of shaft 158 are seated in the bottoms of the radial guide slots 192. At this time rack 194 engages and actuates the mandrel seating limit switch 292 to complete the circuit of the mandrel seating relay winding 294. Energization of the mandrel seating relay winding 294 closes contacts 346 to complete the circuit of

winding 342 to open contacts 260 and close contacts 262 and 264. The opening of contacts 260 interrupts the down drive circuit of armature 254, and the closing of contacts 262 and 264 completes the return drive circuit for armature 254. The circuit of winding 242 is maintained by a holding circuit including winding 348 and contacts 350.

The energization of mandrel seating relay winding 294 also closes the mandrel seating latch contacts 298, 318, and 330 of the respective units. It can be seen by reference to Figure 5 that the closing of contacts 298 associated with windings 296 completes the circuit of these windings from line 234, through windings 296, through contacts 298, through contact 300, and through brush 302 to line 236. Windings 296 may conveniently be those which are associated with the unit 34 positioned adjacent the feed station. The circuit to windings 296 is maintained after brush 302 leaves contact 300 by the holding circuit including winding 312 and normally open contacts 304. When windings 296 are energized, winding 312 is energized to close contacts 304 and maintain the circuit of windings 296 through contact 306 and segment 308 carried by the shaft 26. As brush 302 leaves contact 300 when the reel is stepped, segment 308 remains in engagement with contact 306 to maintain the circuit of windings 296 when the corresponding unit is at the winding station.

It is to be understood that at the time when the parts are as shown in Figure 5, the circuit to seating latch windings 316 associated with the unit adjacent the winding station are maintained by virtue of the engagement of segment 308 with contact 327. These windings 316 were, of course, initially energized during the preceding group of operations. At this time also the latch windings 328 of the unit adjacent the discharge station are de-energized, since their holding circuit was interrupted as segment 308 left contact 340 when the reel was stepped. During the next succeeding group of operations, after that represented in Figure 5, windings 328 will be conditioned to be energized as that unit moves toward the mandrel feed station, and windings 316 are arranged to be de-energized as the corresponding unit arrives at the discharge station.

The closing of the mandrel seating relay winding 294 also closes contacts 376, 408, and 440 associated with the respective mat winding units. The closing of the contacts 376 associated with the unit adjacent the mandrel feed station energizes winding 374 to close contacts 370 and 372 to energize winding 366 to actuate valve 364 to connect lines 356 and 362 of the unit 34 to a source of fluid under pressure, and to connect lines 358 and 360 of the unit to the exhaust. When the lines are so connected, movable rollers 50 and 52 are driven toward one another, as viewed in Figures 1 and 3, to form a pocket of the belt 40 about the empty mandrel. It is to be understood that during this group of operations the solenoid 400 associated with the unit positioned adjacent the winding station is maintained energized by the holding circuit including winding 414 and contacts 416. This winding was initially energized during the preceding group of operations. At the same time the solenoid 432 corresponding to the unit adjacent the discharge station is de-energized, and the solenoid 430 of this unit is energized. When solenoid 430 is energized, the lines 358 and 360 of the associated unit, which may be the unit 38, are connected to a source of fluid under pressure, and the lines 356 and 362 of this unit are connected to the exhaust. When these connections are made, the movable rollers 50 and 52 are driven away from each other to force a wrapped mandrel onto the delivery conveyor 232.

It is to be understood that all the brushes 380, 412, and 444 are carried by the shaft 26 and relatively circumferentially spaced so as to engage a proper segment to energize a proper one of the associated solenoids to

open and close the movable rollers of the corresponding unit. If, for example, we take the unit 34, its solenoid 366 is initially energized when the unit is positioned adjacent the mandrel feed station, and the mandrel seating limit switch 292 is operated. This is accomplished by the energization of winding 374. When the mandrel seating limit switch operates to close contacts 376, the circuit of winding 374 is complete from line 234, through brush 380, through segment 378, through winding 374 and through contacts 376 to line 236. The circuit of winding 374 is maintained after the mandrel seating limit switch is released from line 234, through segment 378, through winding 374, and through contacts 384 to line 236. It will be readily appreciated that the circuit of winding 374 is maintained by the engagement of brush 380 with segment 378 as the reel is stepped through the winding station. When the reel is stepped to advance unit 34 to the discharge station, brush 380 leaves segment 378 to de-energize winding 374 and permit the circuit of solenoid 366 to open. When brush 380 engages segment 394 as unit 34 arrives at the discharge station, the circuit of winding 392 is complete to energize solenoid 368 and reverse valve 364 to open the movable rollers of unit 34. The operation of units 36 and 38 is similar to that of unit 34.

When the mandrel feed rack has been returned to a position where it engages and actuates the return limit switch 460, winding 462 is energized to open the return drive circuit for the mandrel feed drive motor at contacts 352. At the same time, the circuit to the mandrel release latch solenoids 178 is interrupted at contacts 290. The main control relay winding 272 is de-energized by the opening of contacts 282.

The operation of the return limit switch 460 to energize winding 462 also closes contacts 466 so that the reel stepping solenoid 464 is conditioned to operate. It will be remembered that the entry of a length of mat into the space between the source of light 228 and the phototube 230 energized winding 472 to close contacts 474 to initiate operation of the timer 482 by means of winding 478. After a mandrel feed operation is complete and a winding and discharge operation are also complete, timer 482 operates to energize winding 484 to close contacts 468 and thereby complete the circuit of solenoid 464. When the circuit of winding 464 is complete, it operates the actuating member 148 of one-revolution clutch 140 to permit the reel to be stepped through a third of a revolution. When the reel is so stepped, unit 34, which has received an empty mandrel, moves to the winding station; unit 36, the mandrel of which has just been wrapped with a length of mat, moves to the discharge station; and the unit 38, which has just discharged a wrapped mandrel, moves to the mandrel feed station. The machine is then ready for a new group of operations to be initiated by the entry of another length of mat into the space between the light source 228 and the phototube 230. It will be remembered that segment 308, brush 302, and brushes 380, 412, and 444 are all stepped as the reel is stepped. Consequently, both the mandrel seating latches 216 and the movable roller drive cylinders of all the units are conditioned to operate properly on the next group of operations of the machine. If when operations are being commenced so that no winding occurs at the winding station and therefore timer 482 does not operate to close contacts 468, the push button 488 may be operated to step the reel to carry a mandrel which has just been fed to a winding unit to the winding station. Operations thereafter will follow automatically. If at any time during the course of operation it is desired to stop the machine, the push button 287 may be operated. Also, if desired, suitable overwrap limit switches and limit switches responsive to a proper latching of a mandrel shaft end with the bottoms of slots 192 may be provided. Such switches are disclosed in my co-pending application Serial No. 425,837.

While I have shown my mat machine as including only a single reel carrying only one mandrel at each station, it will readily be appreciated that a number of reels or a reel capable of handling more than a single mandrel at a time at a station could conveniently be employed with a common drive and control system.

It will be seen that I have accomplished the objects of my invention. I have provided an automatic indexing multiple unit mat winding machine which is capable of an extremely high rate of production. My machine includes a number of mat winding units on which various operations are simultaneously accomplished. Further, my machine is provided with means for automatically stepping the units from station to station after a group of operations have been completed. My automatically indexing multiple unit mat winding machine is particularly adapted to produce windings of small diameter or mat windings which have thin walls. Consequently, my machine is adapted to take advantage of the potential productive capacity of a production line when such small diameter or thin-walled windings are being made.

It will be understood that certain features and sub-combinations are of utility and may be employed without reference to other features and subcombinations. This is contemplated by and is within the scope of my claims. It is further obvious that various changes may be made in details within the scope of my claims without departing from the spirit of my invention. It is therefore to be understood that my invention is not to be limited to the specific details shown and described.

Having thus described my invention, what I claim is:

1. A mat winding machine for winding lengths of mat about mandrels including in combination a mat winding unit including a belt adapted to be actuated to form a pocket for receiving an empty mandrel to be wrapped and to discharge a wrapped mandrel and drive means for driving said belt to wrap a length of mat about the mandrel, movable means mounting said mat winding unit for movement therewith, means positioned adjacent said mounting means for feeding an empty mandrel to said mat winding unit, means positioned adjacent said mounting means spaced from said mandrel feeding means for feeding a length of mat to said mat winding unit, means positioned adjacent said mounting means spaced from said mandrel feeding means and said mat feeding means for receiving a wrapped mandrel from said mat winding unit, and means for stepping said mounting means successively to position said unit adjacent said mandrel feeding means and said mat feeding means and said wrapped mandrel receiving means.

2. A mat winding machine as in claim 1 wherein said mat winding unit mounting means is a reel.

3. A mat winding machine as in claim 1 wherein said mounting means is formed with means for receiving the ends of a mandrel and latches for seating said mandrel ends in said receiving means.

4. A mat winding machine as in claim 1 wherein said mounting means is formed with means for receiving the ends of a mandrel, latches operable to seat said mandrel ends in the receiving means, and means for operating said latches to seat a mandrel when said unit receives a mandrel from the mandrel feeding means and for releasing said latches to release the mandrel when the unit arrives at the wrapped mandrel receiving means.

5. A mat winding machine as in claim 1 wherein said mat winding unit includes a plurality of belt supporting rollers for said belt, said drive means rotating one of said rollers to drive said belt, at least a pair of said rollers being relatively movable with respect to each other, drive means operable selectively to move said movable rollers toward each other and to move said movable rollers away from each other, and control means for energizing said drive means to move said movable rollers toward one another to form a pocket of said belt about

a mandrel received by the unit from said mandrel feeding means and for energizing said drive means to move said rollers away from each other when said unit is positioned adjacent the wrapped mandrel receiving means.

6. A mat winding machine as in claim 1 wherein said mat winding unit comprises a plurality of belt supporting rollers for said belt, said drive means driving one of said rollers to drive said belt, at least a pair of said rollers being relatively movable with respect to each other, means

10 including a double acting fluid pressure cylinder for selectively moving said movable rollers toward and away from each other, a source of fluid under pressure, a reversible valve for controlling the flow of fluid under pressure from said source to said cylinder, and means for actuating said valve to move said relatively movable rollers toward one another to form a pocket of said belt about a mandrel received by said unit from the mandrel feed means and to move said rollers away from each other to open said pocket when the unit arrives at the wrapped mandrel receiving means.

7. A mat winding machine as in claim 1 wherein said empty mandrel feed means includes a rack for holding a supply of mandrels, a feed latch for retaining said mandrels on said rack, and means for releasing said latch to feed a mandrel to said mat winding machine when the unit is positioned adjacent the empty mandrel feed means.

8. A mat winding machine for winding lengths of mat about mandrels including in combination a plurality of mat winding units each comprising a belt adapted to be actuated to form a pocket for receiving an empty mandrel

30 to be wrapped and to discharge a wrapped mandrel and means for driving the belt to wrap a length of mat about a mandrel, means mounting said mat winding units in spaced relationship to each other, mandrel feed means 35 for feeding an empty mandrel to a first one of said mat winding units, means for feeding a length of mat to a second one of said units when said first unit is at a position to receive an empty mandrel, means for receiving a wrapped mandrel from a third one of said units when said first unit is at a position to receive an empty mandrel and said second unit is at a position to receive a length of mat, and means for stepping said mat winding unit mounting means successively to position each of said units adjacent said mandrel feeding means and said 40 mandrel feeding means and said wrapped mandrel receiving means.

9. A mat winding machine as in claim 8 wherein each of said mat winding units includes a plurality of belt supporting rollers for supporting the belt of each unit, 50 said drive means comprising a common drive means for driving one roller of each unit to drive all of said belts.

10. A mat winding machine as in claim 8 wherein said mounting means is a reel, the arrangement being such that said units are spaced circumferentially around said reel, 55 one of said units being positioned adjacent each of said mandrel feed means and said mat feeding means and said wrapped mandrel receiving means whereby a mandrel feed operation and a winding operation and a discharge operation take place after each stepping operation.

11. A mat winding machine for winding lengths of mat about mandrels including in combination a mandrel feed station, a winding station, a discharge station, a plurality of mat winding means each comprising a belt

60 adapted to be actuated to form a pocket for receiving an empty mandrel to be wrapped and to discharge a wrapped mandrel and means for driving the belt to wrap a length of mat about a mandrel, means mounting said mat winding units such that one of said units is positioned adjacent each of the respective stations, and means for 65 stepping said mounting means to position each of said units successively adjacent each of said stations.

12. A mat winding machine as in claim 11 wherein each of said units includes a plurality of belt supporting rollers 70 for each of said belts, said drive means driving one roller

of each unit to drive said belts, at least a pair of said rollers of each unit being relatively movable toward one another to form a pocket of the belt about a mandrel received by the unit and away from each other to discharge a wrapped mandrel from the unit, means for moving the movable rollers of each unit, and control means for actuating the roll moving means of the unit positioned adjacent the mandrel feed station to form said pocket when said unit receives a mandrel and for actuating the roll moving means of the unit positioned adjacent the discharge station to open said pocket to discharge a wrapped mandrel.
